By Attorney

George L. Martin

UNITED STATES PATENT OFFICE.

WILLIAM A. STOWE, OF NEW YORK, N. Y.

DESIGN FOR A DIRECTION INDICATOR AND STOP LIGHT.

Application filed March 7, 1923. Serial No. 5,385. Term of patent 3½ years.

To all whom it may concern:

Be it known that I, WILLIAM A. STOWE, a direction indicator and stop light, showing citizen of the United States, residing in my new design, and the city, county, and State of New York, have invented a new, original, and ornamental Design for Direction Indicator and Stop Light, of which the following is a specification, reference being had to the accompanying drawing, forming a part

Figure 1 is an elevational view of a

Figure 2 is a side view in elevation of Figure 1.

I claim:

The ornamental design for a direction indicator and stop light.

WILLIAM A. STOWE.
